UNITED STATES PATENT OFFICE.

CHARLES JEFFERSON SYKES, OF CHICAGO, ILLINOIS, ASSIGNOR TO THE SCHOLL MANUFACTURING COMPANY, OF CHICAGO, ILLINOIS, A CORPORATION OF NEW YORK.

ARCH-FITTING MACHINE.

1,190,812.

Specification of Letters Patent.

Patented July 11, 1916.

Application filed May 1, 1915. Serial No. 25,314.

To all whom it may concern:

Be it known that I, CHARLES JEFFERSON SYKES, a citizen of the United States, residing at Chicago, in the county of Cook and State of Illinois, have invented certain new and useful Improvements in Arch-Fitting Machines, of which the following is a specification.

My invention relates to improvements in arch fitting machines for shaping or adjusting the metallic parts of instep arch supports.

Among the objects of my invention is to provide a structure which is simple, cheap, easy to manipulate, powerful in action, and readily adjustable to requirements of use.

In the drawings, wherein I have shown an embodiment of my invention Figure 1 is a side elevation of the arch fitter; Fig. 2 is a longitudinal section therethrough on line 2-2 of Fig. 3; Fig. 3 is a plan view, a portion of the handle being broken away; Fig. 4 is an end elevation; Fig. 5 is a vertical section on line 5-5 of Fig. 1; and Fig. 6 is a vertical fragmentary section on line 6-6 of Fig. 2.

In the drawings 10 indicates the frame provided with an anvil portion 11, with which coöperates a pressure head 12 carried by a slide bar 13 guidably mounted to slide in the frame, under the control of an operating lever 14, which is pivoted to the base for manual operation. Specifically the frame 10 comprises a base 16, above which rise parallel side walls 17-17 connected at their front by the anvil casting 11 and at their rear end by cross-bar 18. The anvil is preferably made integral with the frame and has the pressure receiving face at its front end at a proper height to permit the slide bar 13 to pass therebelow. The brace 18 is also disposed above the path of the slide bar 13, so that the frame provides a channel or slide way for the slide bar 13 open at both ends. The slide bar 13 is made preferably of channeled construction for lightness, with side walls 20-20 connected by an end wall 21 and with its front end merging into a broadened pressure arm 22 that extends up into alinement with the broad anvil face and that carries the pressure head 12. For operating the slide bar the lever 14 is pivoted as at 24 between the side walls 17-17 back of the anvil, and may rock rearwardly through the slot that is

left between the side walls above the brace 18. The lower end of said lever is channeled as at 27 and within the channel is pivoted, as at 28, to one end of a connecting link 30, the other end of which extends 60 down into the channel of the slide bar 13 and carries a cross pin 31 that slides in slots 32-32 formed in the side walls of the slide-bar. An adjustable screw 33 extends through the rear wall 21 of the slide 65 on a level with the slots 32 to limit adjustably the range within which the pin 31 may slide in the slots 32, varying the extent to which the slide bar 13 can be moved by oscillation of the lever 14. The connecting link 30 is given a curvature, somewhat S shaped, so that in its displacement under the lever operation it may not interfere with the brace 18, although its pin-carrying end of the link moves in a path 70 75 beyond said brace.

When the lever 14 is forced down to the end of its throw, resting on cross bar 18, a toggle lock is formed holding the head 12 from movement away from the anvil and 80 leaving the operator's hands free to work on the rigidly held arch support. The position of the sliding head with respect to the anvil face when the toggle lock comes into action will, of course, depend upon the position of the adjusting screw 33. When the screw is turned to a point near its inner limit of movement as in Fig. 2, the structure operates as a vise without locking the head in place, and the handle moving to 90 the dotted line position draws the head against the anvil without swinging the link pivot past dead center.

The active face of the anvil 11, as shown at 40, is given compound curvatures, representing approximately the maximum curvatures that may be required in instep arch adjustment, said surfaces being concaved when viewed in plan as in Fig. 3 and convexly curved when viewed in cross section, 100 as in Fig. 2, after the fashion of the maximum expected curvatures of the plantar surface of the human instep.

The pressure head 12 is generally a block, preferably made of wood and faced with 105 leather as at 41, said block being convexly curved in plan at its front face and at its rear face made flat, with a dovetailed groove 42 to interfit with the dovetail projection 43, that is formed on the inner face of arm 22. 110

Of course pressure blocks of different shapes may, interchangeably, be applied to the arm.

In the upper surface of the anvil, where it is firmly bridged across the side walls of the frame or base, I provide a recess 45 shaped approximately to represent the maximum curvatures that may be desirable for the formation of an anterior-metatarsal-arch-supporting protuberance in the forward portion of a metallic arch support.

In operation an arch support to be fitted has its metal plate portion placed in the space between the anvil and pressure block, (to which space a commercial arch support 15 is preliminarily formed more or less closely to correspond); then by the operation of the lever, under proper adjustment of screw 33, any desired pressure may be applied to spring the bottom part of the arch support between the anvil and the pressure block into the desired curvature, and by employing a hammer and peening the flared inner curved portion of the arch support over the convexly curved portion of the anvil, the metal 20 plate may be given a set in the desired curvature. For formation of anterior metatarsal supporting protuberances the front portion of the arch plate is held over the depression 45 and the operator using a hammer 25 peens the metal into the depression 45 to the desired degree.

While I have herein described in some detail a particular embodiment of my invention it will be apparent to those skilled in the art that changes in detail might be made without departure from the spirit thereof and within the scope of the appended claims.

Having described my invention what I claim is:

40 1. In an arch support fitting machine, the combination of a frame carrying an anvil and provided with a guide way, a slide bar in said guide way having an arm confronting the anvil and carrying a pressure head 45 to coöperate with said anvil, a lever above said slide bar positioned at the side of the anvil away from the head and working in the direction of slide movement, a link connection between said lever and said slide bar, and means for varying the throw of said slide bar.

2. In an arch support fitting machine, the combination of a frame carrying an anvil and provided with a guide way, a slide bar 55 in said guide way having an arm confronting the anvil and carrying a pressure head to coöperate with said anvil, a lever above said slide bar, working in the direction of slide movement, a link connection between 60 said lever and said slide bar, and having a slot and pin connection with said slide bar.

3. In an arch support fitting machine, the

combination of a frame carrying an anvil and provided with a guide way, a slide bar in said guide way having an arm confronting the anvil and carrying a pressure head 65 to coöperate with said anvil, a lever above said slide bar, working in the direction of slide movement, a link connection between said lever and said slide bar, having a slot 70 and pin connection with said slide bar and means for adjusting the amount of lost motion permitted between the link and slide bar.

4. In an instep arch fitting machine the 75 combination of a base, an anvil carried thereby, having a concaved surface at its end, a slide bar sliding below said base having a pressure arm extending upward to confront said anvil, said slide bar having a channel in 80 its rear portion open at its top, a lever pivoted above said slide bar at the side of the anvil away from the pressure arm, and a link connection between said lever and said slide bar, said link extending into said chan- 85 nel of said slide bar.

5. In an instep arch fitting machine the combination of a base, an anvil carried thereby, having a concaved surface at its end, a slide bar sliding below said base having a 90 pressure arm extending upward to confront said anvil, said slide bar having a channel in its rear portion open at its top, a lever pivoted above said slide bar, a link connection 95 between said lever and said slide bar, said link extending into said channel of said slide bar, said link at its lower end carrying a transverse pin and the side walls of said slide bar recess having slots therein to receive said pin, and an adjusting screw carried by said slide bar for limiting the play of said pin in said slots.

6. In an instep arch fitting machine the combination of a base, an anvil carried thereby and having a concaved surface at its end, 105 a slide bar having a pressure arm confronting said anvil, a lever pivoted to the base, a link having one end pivotally connected to the lever and the other end pivotally connected to the slide bar, the pivotal connections being positioned with respect to the lever pivot to form a toggle lock when the lever is at the extreme end of its operating stroke, and means to shift the pivotal connection between the link and slide to vary 110 the position of the arm with respect to the anvil when the lever is in locked position.

In testimony whereof I hereunto set my hand in the presence of two subscribing witnesses.

CHARLES JEFFERSON SYKES.
